UNITED STATES PATENT OFFICE.

MORRIS CITRIN, OF BROOKLYN, NEW YORK.

ASH SIFTER.

Application filed January 2, 1926. Serial No. 78,749.

This invention relates to fireproof ash sifters and has for its object the production of a construction which is simple and inexpensive of manufacture but effective in 5 operation.

Another object includes the provision of a dust and fireproof ash sifter wherein the several parts are separable units, thereby permitting replacement of any part or parts 10 as they become worn or damaged.

Other objects will appear hereinafter, and I attain these objects by the construction illustrated in the accompanying drawing in which—

Fig. 1 is a view in perspective of a construction which embodies the principles of 15 my invention.

Fig. 2 is a section taken on the line 2—2 of Fig. 1.

Fig. 3 is an enlarged view of the lower portion of one form of my construction similar to that shown in Fig. 1 with the ash pan or tray in position.

Fig. 4 is a plan view of a slightly modified form of construction which embodies 20 the principles of my invention.

Fig. 5 is a section taken on the line 5—5 of Fig. 4.

Fig. 6 is a section of the ash pan provided with an opening in the bottom thereof.

Like numerals refer to the same parts throughout the several views.

It is among the prime purposes of my invention to save coal, and to this end I provide a safe and convenient sifter for separating the ashes from the unburned coal. My invention contemplates the use of simple and convenient means for accomplishing the above results, whereby the sifted ashes are 35 deposited while the unburned coal and heavier particles are disposed in such a manner as to be readily accessible for use.

I have found that by liberally moistening the furnace products before sifting, I 40 not only avoid making dust but thus restore and enliven the unburned coal, so that when the sifted and moistened coal is used on the hot coal bed in the furnace for firing a hotter fire is produced with more complete combustion than when unburned coal is used 45 without moistening. With the above and other objects in view, I have devised and constructed the ash sifting device illustrated in the accompanying drawing wherein I 50 provide, preferably, a rectangular screen

frame 10 of suitable dimensions so as to meet the requirements to which the screen is put. For the ordinary householder the dimensions are comparatively small and need not exceed three feet in the larger dimension. This frame is covered in any suitable way by screen 11. The frame 10 and screen 11 may be called the screening unit which may be of any suitable construction so that the screen is integral with the frame, and the frame may be separable from the support or it may form a part of the support. The screening unit is supported in any suitable manner by a supporting member. The screening support comprises a rectangular 60 back 13 and triangular side walls 14. It is obvious that this construction of supporting member is open at the bottom and forms with the screening unit a suitable sifter device for separating the unburned coal from 65 the ashes. In order to facilitate the removal of ashes I provide a suitable ash tray or pan 15. This pan comprises a rectangular member of suitable dimensions to receive the supporting member and may be of any desired depth. In the construction shown, I have illustrated and shown side walls 16, 16, as comparatively shallow. These, of course, may be deeper so as to take care of a greater quantity of ashes if desired. 70

In the form illustrated in Figs. 4 and 5, I have shown a frame supporting member in the form of an enclosed rectangular casing open at each end and having a door 17 in the front wall 18. The back wall 19 is of 75 rectangular shape and is in general of similar construction to that of the supporting frame unit 12. The side walls are of full rectangular construction so as to completely enclose the screening unit 11 and its frame. 80 The lower end of the rectangular supporting unit of this construction is adapted to receive the tray 15 similar to the one described in connection with Figs. 1, 2 and 3. This pan may for convenience be provided 85 with an opening 20 in the bottom thereof and this opening is temporarily closed with a slidable gate 21. This gate is so constructed as to be removable when the tray is placed on an ash can or barrel, thereby affording convenient means for emptying the tray. To prevent the possibility of dust 90 escaping while the ashes are being sifted, I provide a cover 22 which fits over the top of the rectangular casing. This cover is 95 100 105 110

provided with trap doors 23 and 24 which are held in position with spring hinges 25 so as to automatically remain closed. The front door 17 in the casing 18 is likewise provided with a suitable spring 25 to retain the door normally shut.

When this type of ash sifter is used, it is only necessary to place the properly moistened ashes on top of trays 23 and 24 which 10 will then automatically swing downward in the position indicated by dotted lines and thereby permit the ashes to drop on to the screen 11. The finer material, of course, drops through into the tray 15, while the 15 coarser material automatically rolls out in front through the door 17. This door is opened by the weight of the material pushing against it, and is closed when the material is passed through. By the automatically 20 operating doors I provide against the liberation of dust which possibly may be caused by the screening of the ashes.

It is understood that the tray illustrated

in Fig. 6 may be used in place of tray 15, if desired.

While I have described specific embodiments of my invention, it is of course understood that various modifications are possible, which fall wholly within the spirit and scope of my invention. I do not, therefore, desire to be understood as having limited myself unduly by the specific constructions herein disclosed. What I claim, therefore, as new and useful, of my own invention and desire to secure by Letters Patent is:

A fireproof ash sifter comprising a unitary supporting member, a screening unit consisting of a frame and a screen thereon, said frame removably held in said supporting member, a tray engaging the open end of the 40 supporting member, and a gate in said tray.

In testimony whereof I have hereunto set my hand on this 16th day of November A. D., 1925.

MORRIS CITRIN.
